GUARD DEVICE FOR SEWING MACHINES

Henry C. Nissen, Stratford, Conn., assignor to
The Singer Manufacturing Company, Elizabeth, N. J., a corporation of New Jersey

Application September 14, 1940, Serial No. 356,748

8 Claims. (Cl. 112—261)

This invention relates to guards for sewing machines, and more particularly to a sewing machine provided with a trimmer mechanism and having a loop-taker rotating about an axis substantially parallel to the path of needle-reciprocation.

The primary object of this invention is to provide means obviating fouling of the loop-taker of a sewing machine by trimmed-off portions of the work, and especially in a sewing machine in which the work is trimmed close to the point of stitch-formation.

Other and more specific objects of the invention will be apparent from the following description and claims.

The invention consists in the guard device as hereinafter described in connection with the accompanying drawing which illustrates a preferred embodiment of the invention and in which:

Fig. 1 is a top plan view of a portion of the bed-plate of a sewing machine containing the improved guard device, the usual bed-slide being removed and the movable trimmer-knife being shown in section. Fig. 2 is a front side elevation, partly in vertical section, of the loop-taker bracket, trimmer-knife and feed-dog as associated in the machine, the section being taken substantially on the line 2—2 of Fig. 1. Fig. 3 represents a perspective view of the loop-taker and feed-dog guard, shown partly broken away. Fig. 4 is a bottom plan view of the throat-plate and attached ledger-blade. Fig. 5 represents a perspective view of the throat-plate, with the ledger-blade omitted.

Referring to the drawing, the sewing machine has the usual work-support or bed-plate 1 provided with an opening 2 overhung by a throat-plate 3; the throat-plate being secured at its opposite ends upon the bed-plate 1 by screws 4. The throat-plate 3 is provided with an aperture 5 to receive the usual vertically reciprocating eye-pointed needle 6, said throat-plate also having feed-slots 7 through which the feed-dog 8 is upwardly projected to advance the work.

The throat-plate 3 is formed or cut away to provide a depression 9 in the upper face of the throat-plate directly in front of the needle-aperture 5. The depression 9 of the throat-plate is adapted to receive the delivery end of a transverse binder (not shown), of any usual or suitable construction. The side portion of the throat-plate directly in front of the depression 9 is cut away to provide an edge-wall 10 extending transversely of the line of seam formation and defining the rearward portion of a clearance recess 11 in the side edge of the throat-plate 3.

The front end portion of the throat-plate 3 is recessed to receive the shank of a ledger-blade plate 12 secured upon the throat-plate by the front throat-plate securing screw 4. The plate

12 has a ledger-blade 14 overlying the side margin of the throat-plate directly adjacent the feed-dog 8 and extending rearwardly to the throat-plate recess 11.

5 The outer edge of the ledger-blade 14 at the rearward end thereof extends substantially parallel to the line of seam formation, and coacting with said edge in severing work is a movable trimmer-knife 15 attached to a carrier-arm 16 which may be actuated in any usual or suitable manner. It will therefore be understood that the trimmer-knife acts to sever the work closely in front of the needle and at one side of the line of seam formation.

15 Complemental to the needle 6 in the formation of lock-stitches is a loop-taker 17 of the vertical-axis rotary hook type, i. e., of the type in which the axis of rotation of the loop-taker is substantially parallel to the path of reciprocation of the needle. The loop-taker 17 has the usual upwardly open cup-shaped body provided in the cylindrical side wall thereof with a needle-thread loop seizing beak 18. Suitably journaled in the loop-taker 17 and restrained against rotation therewith is an upwardly open bobbin-holder 19 receiving a bobbin 20. The bobbin 20 is removably retained in the holder 19 by a latch 21 and the thread wound upon the bobbin is interlocked with the needle-thread in the formation of 20 stitches.

25 The loop-taker 17 is rotated about a vertical axis by actuating mechanism in part carried by a bracket or hook-saddle 22, the loop-taker 17 being disposed above the upper face 22' of the hook-saddle and partly underlying the throat-plate 3. The hook-saddle 22 is disposed below the bed-plate, and in the present case the loop-taker and hook-saddle are similar to those disclosed in the U. S. patent to W. Myers, No. 2,095,-

30 450, Oct. 12, 1937.

35 The present invention relates more particularly to the provision of means for guarding the loop-taker 17, which rotates at high speed during the operation of the machine, from entrance and 40 entanglement by trimmed-off work-margins which are deflected downwardly through an opening 23 provided in the bed-plate 1 in front of the loop-taker.

45 To this end, there is provided a stationary 50 segmental guard-member having a curved side wall 24 conforming in curvature to and encompassing the front portion of the cylindrical side wall of the loop-taker 17 in close proximity thereto. Extending outwardly from the lower portion 55 of the side wall 24 of the guard-member is a supporting shank 25 which is apertured to receive screws 26 for rigidly securing the guard-member upon the upper face 22' of the hook-saddle 22.

55 The curved side wall of the guard-member is provided at the upper edge thereof with an in-

wardly extending flange 27 overhanging a segmental portion of the rim of the loop-taker 17 and of the bobbin-holder 19, said flange 27 exposing the bobbin 20 for removal thereof. To facilitate removal of the bobbin 20 from the loop-taker 17, the guard-flange 27 is provided in the horizontally flat upper face thereof with a notched recess 28 affording access to the upper rim of the bobbin. The under face 27' of the guard-flange is preferably inclined downwardly from the inner free edge of said flange to add to the rigidity of the guard-member.

At one end of the guard-member, the upper face of the flange 27 thereof is partly cut away to provide a transverse shoulder 29 and a depressed land 30. The flange-land 30 underlies the throat-plate depression 9, as illustrated by dotted lines in Fig. 1 of the drawing. Extending substantially tangentially and forwardly from the flange-land 30, under the throat-plate, is a guard-wing 31, of which the upper edge is disposed close to the under side of the throat-plate. The guard-wing 31 is also disposed closely adjacent to the portion of the feed-dog 8 in advance of the needle and at the trimmer side of said feed-dog, thereby to guard the feed-dog from engagement by trimmed-off portions of the work.

The guard-flange shoulder 29 extends transversely of the line of seam formation into the throat-plate recess 11, the upper edge of the shoulder 29 being substantially even with the upper face of the throat-plate depression 9. It will therefore be understood that the guard described effectively shields the loop-taker 17 and feed-dog 8 from entanglement by trimmed-off portions of the work, thus permitting the trimming operation to be performed closely in front of the needle and thereby facilitating the handling of the work, without interfering with the operation of the loop-taker 17 or the removal of the bobbin 20 therefrom.

Having thus set forth the nature of the invention, what I claim herein is:

1. In a sewing machine having an endwise reciprocatory eye-pointed needle, and a loop-taker rotating about an axis substantially parallel to the path of needle-reciprocation, the improvement which consists in the provision of a stationary segmental guard-member partly encompassing said loop-taker in close proximity thereto, said guard-member having a flange overhanging a portion of said loop-taker.

2. In a sewing machine having an endwise reciprocatory eye-pointed needle, and a loop-taker rotating about an axis substantially parallel to the path of reciprocation of the needle, said loop-taker having an upwardly open cup-shaped body, the improvement which consists in the provision of a curved guard-member partially encompassing the cylindrical side wall of said loop-taker body, said guard-member overhanging the rim of said body, and means detachably securing said guard-member in loop-taker shielding position.

3. In a sewing machine having an endwise reciprocatory eye-pointed needle, a loop-taker rotating about an axis substantially parallel to the path of needle-reciprocation, and a hook-saddle bracket in which said loop-taker is rotatably journaled, the improvement which consists in the provision of a loop-taker shielding guard-

member partially encompassing said loop-taker, said guard-member being detachably secured upon said bracket.

4. In a sewing machine having an endwise reciprocatory eye-pointed needle, a loop-taker rotating about an axis substantially parallel to the path of needle-reciprocation, and a hook-saddle bracket supporting said loop-taker, the improvement which consists in the provision of a loop-taker shielding guard-member having a side wall provided with a flange overhanging said loop-taker, said guard-member having a shank detachably secured upon said bracket.

5. In a sewing machine having a work-support including a throat-plate provided with a feed-slot and a needle-aperture, an endwise reciprocatory needle, a loop-taker rotating about an axis substantially parallel to the path of needle-reciprocation, a hook-saddle bracket supporting said loop-taker, and a feed-dog operating through said feed-slot, said work-support having an opening in front of said loop-taker, the improvement which consists in the provision below said work-support of a guard-member extending across the front of said loop-taker and having a wing disposed adjacent said feed-dog forwardly of said needle-aperture, said wing extending substantially parallel to the line of seam formation, and said guard-member being supported by said hook-saddle bracket.

6. In a sewing machine having a work-support including a throat-plate provided with a needle-aperture and a feed-slot, an endwise reciprocatory needle, a loop-taker rotating about an axis substantially parallel to the path of needle-reciprocation, a work-advancing feed-dog operating through said throat-plate feed-slot, a ledger-blade carried by said throat-plate, and a trimmer-knife coacting with said ledger-blade in advance of said needle-aperture in the throat-plate, the improvement which consists in the provision of means for shielding said loop-taker and feed-dog from entanglement by trimmed-off portions of the work, said means comprising a guard-member having a segmental side-wall partially encompassing said loop-taker in close proximity thereto and having a flange overhanging said loop-taker, said guard-member extending under said throat-plate and having a substantially tangential wing extending forwardly therefrom adjacent to said feed-dog, and means for detachably supporting said guard-member in loop-taker and feed-dog shielding position.

7. A loop-taker and feed-dog shielding guard-member for sewing machines, having a segmental side wall provided with an attaching shank and with an inwardly overhanging flange, said side wall having a substantially tangential wing extending from one end of and disposed adjacent to said side wall.

8. A loop-taker and feed-dog shielding guard-member for sewing machines, having a segmental side wall provided with an inwardly overhanging flange, said flange being partly cut away in its upper face at one end thereof to define an abutment-shoulder, and a wing extending substantially tangentially from the abutment shoulder end of said guard-member and disposed adjacent to said side wall.

HENRY C. NISSEN.
